JOHN D. GORDER

By Watson E. Coleman

Attorney

UNITED STATES PATENT OFFICE.

JOHN D. GORDER, OF FREDERICK, SOUTH DAKOTA.

WRENCH.

1,181,380.

Specification of Letters Patent.

Patented May 2, 1916.

Application filed February 21, 1916. Serial No. 79,689.

To all whom it may concern:

Be it known that I, JOHN D. GORDER, a citizen of the United States, residing at Frederick, in the county of Brown and State 5 of South Dakota, have invented certain new and useful Improvements in Wrenches, of which the following is a specification, reference being had to the accompanying drawings.

- 10 This invention relates to an improved wrench and has for its primary object to provide a quick adjustable monkey wrench which is exceedingly simple in its construction as well as highly strong and durable, 15 and is provided with means whereby the adjustable jaw can be securely held in its adjusted position to resist severe strains or pressures devolving thereon in the use of the wrench.
- 20 It is another more particular object of the invention to provide a wrench of the above type including a shank having a fixed jaw on one end and teeth on the opposite edges of said shank, a pair of dogs pivot- 25 ally mounted in the inner end of the adjustable jaw, and bowed springs connecting said dogs and normally acting to hold the free ends thereof in engagement with the teeth on the wrench shank, pressure upon 30 said bowed springs operating to move the dogs out of engagement with the teeth whereby the jaw may be longitudinally adjusted upon the shank.

With the above and other objects in view, 35 my invention consists in the novel features of construction, combination and arrangement of parts to be hereinafter more fully described, claimed and illustrated in the accompanying drawing in which,

- 40 Figure 1 is a perspective view of a wrench constructed in accordance with the preferred embodiment of my invention; Fig. 2 is an edge view partly in section; and Fig. 3 is a horizontal section taken on the line 3—3 45 of Fig. 2.

Referring in detail to the drawing, 5 designates the wrench shank of rectangular form in section, having a suitable handle indicated at 6 attached to one end thereof. 50 On the other end of the shank 5, the fixed jaw 7 is formed. The opposite faces of the shank 5 are each provided with a longitudinal series of teeth 8.

9 designates the adjustable jaw mounted 55 for longitudinal sliding movement upon the shank 5 and having a hollow longitudinally

projecting extension 10 through which the wrench shank is disposed. The opposite side walls of the extension 10 corresponding to the toothed faces of the wrench shank 5, 60 are provided in their inner ends with the recesses or sockets 11 to accommodate the pivot knuckles 13 formed upon one end of the dogs 12. Pivot pins or bolts 14 are disposed transversely through the body walls 65 of the adjustable jaw and through the knuckles 13, said pins supporting the dogs 12 for pivotal movement.

Relatively thin metal bowed springs 15 are riveted or otherwise secured at their 70 extremities to the corresponding longitudinal edges of the dogs 12 intermediate of their ends, said springs extending across the untoothed faces of the wrench shank 5. These springs normally act to hold the free 75 ends of the dogs in engagement with the teeth 8 on the wrench shank and thereby prevent an inward movement of the adjustable jaw 9 upon the shank with respect to the fixed jaw 7.

80 From the foregoing description, the construction and manner of operation of the device will be readily understood.

When it is desired to adjust the jaw 9, the operator presses with his thumb and forefinger upon the central portions of the respective bowed springs 15 and forces the same toward the shank 5, thus tending to straighten the springs. The free ends of the dogs 12 will thereby be forced outwardly 90 and beyond the edges of the teeth 8. The jaw 9 may now be freely moved longitudinally upon the wrench shank until it is properly spaced from the opposed face of the fixed jaw 7, whereby the nut or other object 95 may be engaged between the faces of said jaws. When pressure upon the springs 15 is released, said springs immediately return to their normal condition and draw the free ends of the dogs inwardly into engagement 100 with the teeth 8, thereby preventing a further inward movement of the adjustable jaw. In this manner, it will be apparent that the jaw 9 can be very easily and quickly adjusted upon the wrench shank and will be 105 securely held in its adjusted position thereon to resist any longitudinal pressures or strains to which said jaw will be subjected in ordinary use.

110 It is apparent that the device as a whole is exceedingly durable in its construction and, as but few parts are employed which

are all of simple form, the wrench can be manufactured at comparatively small cost.

The device can, of course, be constructed in various sizes and the wrench jaws formed 5 in any desired shape.

While I have shown and described the preferred construction and arrangement of the several elements, it is to be understood that the same are susceptible of considerable 10 modification therein and I, therefore, reserve the privilege of adopting all such legitimate changes as may be fairly embodied within the spirit and scope of the invention as claimed.

15 Having thus fully described my invention, what I desire to claim and secure by Letters Patent is:—

1. In a wrench, the combination of a shank having a fixed jaw on one end and spaced teeth on the opposite faces of the shank, a longitudinally adjustable jaw engaged upon said shank, pivoted pawls carried by said adjustable jaw, and a bowed leaf spring fixed at its extremities to said 25 pawls intermediate of their ends and normally holding the free ends of the pawls in engagement with the teeth on the respective faces of the wrench shank, pressure upon the medial portion of the spring acting to 30 force the free ends of the dogs outwardly and disengage the same from said teeth

whereby the adjustable jaw may be shifted upon the shank with respect to the stationary jaw.

2. In a wrench, the combination of a shank 35 having a fixed jaw on one end and teeth upon the opposite faces of said shank, an adjustable jaw mounted upon the shank and having a tubular body portion through which the shank is disposed, dogs pivotally 40 mounted in the inner end of the adjustable jaw body, bowed leaf springs fixed at their extremities to the corresponding edges of said dogs intermediate of their ends and normally holding the free ends of the dogs 45 in engagement with the teeth on the opposite faces of the shank, said springs extending across the untoothed faces of the shank and having their medial portions spaced therefrom, said springs being adapted to be 50 pressed inwardly toward the shank whereby the free ends of the dogs are forced outwardly and disengaged from the teeth on the wrench shank to permit of a longitudinal adjustment of said adjustable jaw. 55

In testimony whereof I hereunto affix my signature in the presence of two witnesses.

JOHN D. GORDER.

Witnesses:

ARTHUR G. PORTER,
M. A. MARETHLD.
